UNITED STATES PATENT OFFICE.

FRANK S. WEAVER, OF MOUNT HOLLY, NEW JERSEY.

DESIGN FOR A CHAIN-LINK BLANK.

SPECIFICATION forming part of Design No. 32,107, dated January 16, 1900.

Application filed December 16, 1899. Serial No. 740,604. Term of patent 31 years.

To all whom it may concern:

Be it known that I, FRANK S. WEAVER, a citizen of the United States, residing at Mount Holly, in the county of Burlington and State 5 of New Jersey, have invented and produced a new and original Design for a Chain-Link Blank, of which the following is a specification.

This invention relates to a new and original design for a chain-link blank, and the essential feature resides in the similar shape of connected link members, which will be more fully hereinafter referred to.

The accompanying drawing represents a 5 plan view of a chain-link blank embodying the features of the design.

The numerals 1 and 2 designate the opposite similar members of the chain-link blank, which have intermediate concaved edges 3 10 and substantially circular ends 4, which are free and provided with circular openings 5, one of said openings being formed in each

free end. The opposite portions of the members 1 and 2 are continued into a flat web 6, having rounded corners 7, a transverse 25 straight edge 8, and opposite circular openings 9. The outer concaved edges 3 continue into the circular ends 4 and the curved corners 7, and the inner concaved edges 3 connect at a point between the circular openings 30 9 at one extremity and merge into the curved ends 4 in a manner similar to the outer edges 3.

Having thus described the invention, what is claimed as new is—

The design for a chain-link blank, herein shown and described.

In testimony that I claim the foregoing as my own I have hereto affixed my signature in the presence of two witnesses.

FRANK S. WEAVER.
